UNITED STATES PATENT OFFICE.

OTTO W. SCHAUML, OF PHILADELPHIA, PENNSYLVANIA.

MEANS FOR SECURING SHUTTLE-BLOCKS TO LOOM-BATTENS.

SPECIFICATION forming part of Letters Patent No. 617,191, dated January 3, 1899.

Application filed April 11, 1898. Serial No. 677,130. (No model.)

To all whom it may concern:

Be it known that I, OTTO W. SCHAUML, a citizen of the United States, residing in Philadelphia, county of Philadelphia, and State of Pennsylvania, have invented certain new and useful Improvements in Means for Securing Shuttle-Blocks to Loom-Battens; and I do hereby declare the following to be a full, clear, and exact description of the invention, so as will enable others skilled in the art to which it appertains to make and use the same, reference being had to the accompanying drawings, and to letters of reference marked thereon, which form a part of this specification.

This invention relates to improvements in shuttle-blocks and battens for looms; and its object is to provide simple and effective means for removably securing the shuttle-blocks to said battens, thus forming a strong and durable construction and permitting the quick and ready attaching and detaching of said blocks when necessary or desired.

The invention consists of the means for removably securing the shuttle-blocks to the battens and in the combination and arrangement of the various parts, substantially as will be hereinafter more fully described and claimed.

In the accompanying drawings, in which like letters of reference indicate corresponding parts in each of the several views, Figure 1 is a front elevation of a portion of a batten, partly in section, and of three shuttle-blocks arranged thereon and provided with my improvements; Fig. 2, an enlarged sectional view on the line $x-x$ of Fig. 1, the actuating pinion and its axle being shown in full; and Fig. 3, an enlarged detail top plan view of one of the shuttle-blocks and of its clamping means.

In said drawings, a represents the batten, provided in its top portion with an elongated groove in which is slidably arranged the actuating rack-bar b for the pinions c in the shuttle-blocks d , which pinions are revolvably mounted on pins or axles e in any desired manner. The rear portion of the top of the batten a is inclined or beveled, as at f , and supports the shuttle-blocks d , which are each provided with a bottom surface g , in-

clined correspondingly with the bevel f of the batten.

Each shuttle-block is held in normal position by means of clamps or brackets o , constituting a backing for the shuttle-block and having their lower ends secured to the batten a by means of screws m , or in any desired manner, while the upper portion of each bracket carries an arm or projection o' , provided with an aperture o^2 , in which is adjustably arranged a set-screw o^3 , adapted to bear upon a metallic disk o^4 , arranged in a socket o^5 in the recessed top portion of the shuttle-block. It must be remarked that the bottom of the socket o^5 is inclined reversely to the plane of the inclined bottom surface of the shuttle-block, by which arrangement a firm and accurate connection between the shuttle-block d and the batten a is attained, as will be manifest.

In the drawings are shown two clamps or brackets for each shuttle-block; but it is obvious that only one clamp or bracket need be used, which in that case engages the central portion of its respective block.

The exposed portions of the actuating rack-bar b are covered by plates r , occupying the space between adjoining shuttle-blocks and removably secured to the batten by screws s or in any desired or well-known manner.

The vertical brackets or clamps o are connected at or near their top portions by a horizontal brace or connecting rod or bar t , secured to said brackets by screws t' , as clearly shown in the drawings.

To remove the shuttle-block, the screws o^3 are operated and afterward the said block is tilted forward and lifted from its position. To replace the block, it is reseated on the batten and the set-screws are then manipulated sufficiently to clamp the block tightly against the brackets.

From the foregoing it can be seen that the shuttle-blocks can be readily and quickly secured to the batten and that the said blocks will always be true with relation to said batten and are prevented from lateral movement by means of the plates r , as will be manifest.

In the drawings I have illustrated only one form of securing or clamping means for the shuttle-blocks; but it will be obvious that

other means could be applied for the same purpose without deviating from the scope of my invention.

Having thus described my said invention, 5 what I claim as new, and desire to secure by Letters Patent, is—

1. The combination with a lay or batten, of a shuttle-block, a bracket carried by the batten, and means for removably clamping said 10 shuttle-block between the batten and bracket, substantially as and for the purposes described.

2. The combination with a lay or batten, of a shuttle-block removably mounted on said 15 batten, a backing for said shuttle-block and means for removably clamping said shuttle-block against said backing, substantially as described.

3. The combination with a lay or batten, of 20 a shuttle-block removably mounted on said batten, a vertical bracket or brackets carried by said batten and means for removably clamping said shuttle-block against said bracket or brackets, substantially as described.

4. The combination with a lay or batten, of 25 a shuttle-block removably mounted on said batten, a vertical bracket or brackets carried by said batten and means acting in a substantially vertical direction on the block for 30 clamping the same against said bracket or brackets, substantially as described.

5. The combination with a lay or batten, of 35 a shuttle-block removably mounted on said batten, a vertical bracket or brackets carried by said batten and provided with an overhanging projection or projections and means acting from said projection or projections in the direction of the batten for clamping said 40 shuttle-block against said bracket or brackets, substantially as described.

6. The combination with a lay or batten 45 having its rear upper edge beveled, of a shuttle-block removably mounted on the beveled surface of said batten, a vertical bracket or brackets secured to the rear face of and projecting above said batten and means for adjustably clamping said shuttle-block against the beveled surface of said batten and the 50 bracket or brackets, substantially as described.

7. The combination with a lay or batten having its rear upper edge beveled, of a shuttle-block removably mounted on the beveled 55 surface of said batten, a vertical bracket or brackets secured to the rear face of and pro-

jecting above the batten and provided with an arm or projection overhanging said shuttle-block, and a set-screw mounted in said arm and adapted to take against the upper 60 face of said block, substantially as described.

8. The combination with a lay or batten having its rear upper edge beveled, of a shuttle-block removably mounted on the beveled surface of said batten and having its under 65 surface inclined correspondingly to the bevel of said batten, a vertical bracket or brackets secured to the rear face of and projecting above the batten and each provided with an arm or projection overhanging said shuttle-block, and a set-screw mounted in each of 70 said arms, the upper face of said block being provided with a socket or sockets having their bottom walls inclined reversely to the incline of the under surface of said block and 75 adapted to receive the engagement ends of their respective set-screws, substantially as described.

9. The combination with a lay or batten having its rear under surface beveled, of a 80 shuttle-block removably mounted on the beveled surface of said batten and having its under surface inclined correspondingly to the bevel of said batten, a vertical bracket or brackets secured to the rear face of and 85 projecting above the batten and each provided with an arm or projection overhanging said shuttle-block, the upper face of said shuttle-block being provided with a socket or sockets having their bottom walls inclined reversely 90 to the incline of the under surface of said block, a metallic disk mounted in each of said sockets, and a set-screw mounted in each of said arms and adapted to take against its respective disk, substantially as described. 95

10. The combination with a lay or batten having its rear upper edge beveled, of a shuttle-block arranged on the beveled surface of said batten and having its under surface inclined correspondingly to the bevel of said 100 batten, and means for drawing the shuttle-block against the beveled rear portion of the batten, substantially as and for the purposes described.

In testimony that I claim the foregoing I have hereunto set my hand this 6th day of April, 1898.

OTTO W. SCHAUER.
